(57) **CLAIM**

The ornamental design for decking, as shown and described.

DESCRIPTION

FIG. 1 is a top front perspective view of the decking;

FIG. 2 is a front elevational view thereof, the rear being identical thereto;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a top front perspective view thereof.

The decking has been broken in the center to indicate indefinite length. The broken lines are for illustrative purposes only and form no part of the claimed design.
